[57] CLAIM

We claim the vehicle mirror design, as shown and described.

DESCRIPTION

FIG. 1 is a perspective view of a mirror in accordance with the present invention;

FIG. 2 is a rear perspective view thereof;

FIG. 3 is a top plan view thereof;

FIG. 4 is a left elevation view, the right side being a mirror image thereof;

FIG. 5 is a front elevation view thereof;

FIG. 6 is a rear elevation view thereof; and

FIG. 7 is a bottom plan view thereof.

The broken line showing of a vehicle and the support structure for a mirror are for illustrative purposes only and form no part of the claimed design.
